UNITED STATES PATENT OFFICE.

CLIFFORD A. OWENS, OF OWENS, OHIO.

LUBRICATION AND PROTECTION DEVICE FOR LOCOMOTIVE BISSEL PINS.

Application filed May 7, 1923. Serial No. 637,254.

To all whom it may concern:

Be it known that I, CLIFFORD A. OWENS, a citizen of the United States of America, residing at Owens, in the county of Marion 5 and State of Ohio, have invented certain new and useful Improvements in Lubrication and Protection Devices for Locomotive Bissel Pins, of which the following is a specification.

- 10 My invention relates to a lubrication and protection device for locomotive Bissel pins, and has to do with the provision of novel, positive and particularly simple means for insuring normal and continuous operation of 15 the Bissel pin structure with substantially no wear of such structure and its connected parts. It also results in important safety measures in that the locomotive frame is relieved from all damaging shocks or jars to 20 which it might be subject from the front truck structure.

The Bissel pin of a locomotive is the common name used for the vertically reciprocable plug which is connected with the front truck 25 structure of a locomotive. The front truck of a locomotive is mainly for guiding purposes and it is, therefore, free to move up and down as it carries none of the weight of the locomotive proper. The Bissel pin is 30 connected to and controlled by the front truck structure and as the truck move up and down, due to irregularities in the track and other means, the Bissel pin is likewise designed to freely move up and down within 35 a bearing which is usually formed by, and integral with, the front frame of the locomotive. This Bissel pin and front truck structure is a very important and vital part of the balancing and equalizing system of a 40 locomotive, and if for any reason the Bissel pin sticks in its bearing all of the vibrations and shocks of the front truck will be directly absorbed by the locomotive frame instead of being absorbed by the standard 45 spring structure.

In the past, it has been the usual practice to provide a plain vertical bearing in the front deck casting of a locomotive for the reception of the Bissel pin and to depend 50 entirely upon the play between the pin and its bearing to give the necessary freedom of movement to such pin. As a direct result of the use of said structure and the lack of proper protection for the Bissel pin, all 55 locomotives have been subject to an unneces-

sary amount of repair and loss of running time. The front trucks of a locomotive are subject to an innumerable number of shocks or bumps during a single run and it is obvious that the trucks may easily be subjected to hundreds of severe jolts in passing over a single mile of track. It will be obvious, therefore, that unless some protective means is placed between the Bissel pin and its bearing the excessive friction between the reciprocating Bissel pin and its bearing will soon cause uneven wearing and subsequent "galling" or sticking of the Bissel pin in its bearing.

Furthermore, the space between the Bissel pin and the bearing has always been constantly filled with cinders and dirt, either from the smoke stack or the clean out which is located directly above the Bissel pin, which also has caused excessive grinding and wearing of the parts. This sticking and excessive wearing of the Bissel pin and its bearing not only necessitates frequent replacement but it directly affects the general maintenance of the entire locomotive and necessitates frequent repairing of the frame itself.

My invention primarily contemplates the provision of means which will positively insure freedom of movement of the Bissel pin structure at all times with substantially no wear on the bearing surfaces, and which means is of such construction that it may be quickly and easily applied to any locomotive provided with a Bissel pin with no change in the structure thereof. This is accomplished by means of a very simple and compact structure which comprises a specially designed casing for protecting the Bissel pin and its bearing from all dust and dirt and lubricating means carried by such casing for insuring continuous lubrication of the Bissel pin.

More specifically, I have found that although the most damaging and dangerous 100 wear and shock to locomotive parts is that upon the frame, equalizer and spring structure, yet the normal and smooth operation of such structure is directly dependent upon the smooth and free operation of the Bissel pin. Therefore, I have provided a protective outer casing for the Bissel pin, which may be secured to any locomotive bearing casting, and a cover for such casing to completely protect the pin from dust and dirt 105 110

from any source. This casing is preferably of such size as to provide a space around the Bissel pin for the reception of waste or other lubricant absorbing material. This lubricating and protecting device will thus be effective to insure continuous freedom of movement within its bearing structure, with the result that the locomotive frame will be free from any shocks or bumps due to the up and down movement of the truck structure.

Other important advantages of my invention will appear as this description progresses or will be brought out by the claims appended hereto. The various objects of my invention are attained by the structure illustrated in the drawings wherein similar characters of reference designate corresponding parts and wherein—

20 Figure 1 is a diagrammatic illustration of a locomotive and Bissel pin structure with my device applied thereto and showing the manner of connecting this Bissel pin structure with the equalizer structure of the locomotive.

25 Figure 2 is an enlarged, vertical, sectional fragmentary view of the Bissel pin structure and its connected parts and showing in detail the manner of protecting and lubricating the Bissel pin and its supporting bearing.

30 Figure 3 is a diagrammatic fragmentary view of a locomotive front truck structure, a Bissel pin provided with my lubricating and protecting device, and an equalizer structure connecting with said Bissel pin.

35 In the drawings, and with particular reference to Figure 1, the locomotive frame is shown as at 1 and the front truck structure which serves principally as a guide for this frame is shown as at 2. It will be obvious that both the locomotive frame structure and the front truck structure can only be shown conventionally as they may take any form consistent with the different standard types of locomotives.

40 The front truck structure 2 usually consists of standard small truck wheels and their connecting axle 3. Disposed between the truck wheels and designed to support the Bissel pin 4 is the truck support 5. This truck support 5 is preferably provided with a recess 6 for the reception of the lower end of the Bissel pin, and it is also provided with an aperture 7 which is designed to receive a centering pin 8. The centering pin 8 is designed to pass through an aperture in the base of the Bissel pin. It will be obvious that this centering pin will permit of vertical reciprocation of the truck support 5 and Bissel pin 4 and at the same time keep these parts in vertical alignment.

45 The upper end of the Bissel pin 4 is designed to pass through and be supported by a bearing 9 which is preferably integrally formed in the front truck casting 10 of the

locomotive. Thus, as the truck structure 2 moves up and down or is vibrated by irregularities in the track, this up and down movement of the truck structure will be transmitted to the Bissel pin 4 which in turn will reciprocate within the supporting bearing 9. This up and down movement of the truck and Bissel pin structure is preferably absorbed by means of the spring and equalizing structure of the locomotive. The 50 equalizing structure comprises a bar 11, one end 12 of which is designed to be connected to the Bissel pin by means of a suitable slot 13, as best shown in Figure 2. As shown, this end 12 of the equalizing bar may be directly supported by the top of the centering pin 8. The equalizer bar is fulcrumed as at 14 by means of a suitable center pin and center pin bearing. As shown at Figure 1 it is customary to make this center pin bearing adjustable to take care of any desired adjustment in the equalizing or balancing system of the locomotive.

55 The spring structure 15, which comprises a series of springs and connecting links arranged on each side of the locomotive, forms a part of the balancing system of the locomotive and is connected to the rear end 16 of the equalizer bar 11 by a suitable connecting bar or link 17. It will be obvious that this equalizing bar and spring structure not only serves as a means for absorbing the shocks or up and down movement of the truck and Bissel pin structure but that the Bissel pin structure in turn forms an important part of this balancing structure in that it is absolutely necessary that the Bissel pin should be free to move up and down in order to preserve the proper balancing of the locomotive.

60 In order to insure positive up and down movement of the truck and Bissel pin structure I have provided the bearing 9 with a circular casing 18. This casing is preferably designed to be welded on to the bearing casting 9 and is of such a size and shape as to provide a space 19 between the surface of the protruding Bissel pin and the casing. The space 19 is of such a size that it will permit of the packing of a suitable quantity of waste or other lubricant absorbing material around the Bissel pin. The top of the casing 18 is provided with a cover 20 which is also provided with a suitable handle 21 for the easy removal of this cover. I have also provided the cover 20 with a suitable oil hole 22 to permit oiling of the waste and Bissel pin without removing the cover. It will thus be seen that, as the Bissel pin is moved up and down by any vibration of the truck structure, the sides of the Bissel pin will be continuously lubricated by the oil soaked waste contained in the casing 18. As the casing 18 and cover 20 also preclude the entrance of any cinders

or other foreign material around the Bissel pin the continuous lubrication of the Bissel pin and its supporting bearing 9 will thus be effective to insure continuous and smooth freedom of movement of the Bissel pin in its bearing.

In the normal operation of the front truck and Bissel pin structure, the truck will be moved upward by any irregularity 10 in the track and this upward movement will be transmitted to the Bissel pin 4. If this Bissel pin 4 is free to move within its bearing 9 the locomotive frame will be relieved of substantially all jar or vibration and instead this vibration will be transmitted 15 through the equalizer bar 11 and will be absorbed by the standard spring structure 15 of the locomotive. If for any reason the Bissel pin 4 would stick in its bearing 9, due 20 to the lack of lubrication or the entrance of cinders or other foreign material, all the vibration and shocks of the truck structure 2 would be directly transmitted to the locomotive frame instead of being absorbed by 25 the spring structure. This sticking of the Bissel pin would not only seriously damage the locomotive frame but it would also tend to render less effective the important balancing structure of the locomotive.

30 It will be understood that the lubricating and protecting casing 18 and cover 20 may be of any suitable shape and size but in the preferred shape shown it will be seen that I have provided an extremely simple and 35 inexpensive device that will give maximum lubrication and protection to the Bissel pin and at the same time require substantially no repair. It will also be understood that the lubricating means may be of any material and any form as long as the Bissel 40 pin is sufficiently lubricated to insure free-

dom of movement and substantially no wear.

It will be apparent that I have provided 45 an extremely simple but positive lubricating and protecting device for the Bissel pin that may be easily secured to the frame or bearing casting of the locomotive and which will be effective to lubricate and protect the Bissel pin under all conditions of operation. 50 It will also be obvious that by lubricating and protecting this Bissel pin and its supporting bearing I am able to obtain practically continuous service from a structure that has hitherto been frequently subject to 55 repair and replacement. Furthermore, by the use of my invention, I have been able to materially reduce the wear on the front deck casting of the locomotive, on the center pin and center pin bearing of the equalizer, on 60 the hanger bearing at the back end of the equalizer, on the engine truck cradle at the point where the Bissel pin comes in contact with the bearing on the cradle, on the spring rig all the way through and on all parts of 65 the locomotive in general.

Having thus described my invention, what I claim is:

1. In combination with a locomotive truck structure, of a Bissel pin, a bearing, 70 means carried by the locomotive for protecting the Bissel pin and bearing from cinders or any other foreign material and means for lubricating said pin.

2. Locomotive Bissel pin structure comprising means enclosing the top of the Bissel pin for lubricating and protecting the same.

In testimony whereof I hereby affix my signature.

CLIFFORD A. OWENS.
